FORMING APPARATUS

Roy A. Shipley, Pittsburgh, Pa., assignor to National Fireproofing Corporation, Pittsburgh, Pa., a Corporation of Pennsylvania

Application June 20, 1931. Serial No. 545,780

8 Claims. (Cl. 25—39)

This invention relates broadly to forming apparatus, and more particularly to apparatus for use in forming workable material, such, for example, as ceramic material in the "green" state.

It relates still more particularly to forming apparatus adapted for use in forming the ends of conduit sections.

The invention further relates to forming apparatus particularly adapted and intended to cooperate with an extremity of a conduit section, such, for example, as a length of extruded ceramic material in the green state, to provide thereon a generally longitudinally extending projection adapted to interfit with a complementarily shaped extremity of an adjacent section to provide a strong, self-supporting conduit.

I provide forming apparatus, comprising guide means for cooperation with a surface of a conduit section to guide the forming apparatus in movement relatively to the conduit section, and shaping means connected with the guide means and effective upon such relative movement for shaping an end of the conduit section. I further provide forming apparatus, comprising a head having guiding means connected therewith, and shaping means connected with the head and extending below the same for shaping material upon guided movement of the forming apparatus.

Other objects and advantages of the invention will become apparent as the following description of certain present preferred embodiments thereof proceeds.

In the accompanying drawings I have shown certain present preferred embodiments of the invention, wherein

Figure 1 is a longitudinal central cross-sectional view through a portion of a length of extruded ceramic material provided with a central duct;

Figure 2 is a longitudinal central cross-sectional view through portions of a pair of conduit sections having adjacent extremities of complementary shape, and showing such sections in positions to be moved toward one another into interfitting relationship to form a conduit;

Figure 3 is a longitudinal central cross-sectional view through a portion of a conduit length showing forming apparatus in position to shape an end of such length and after the shaping operation has been completed;

Figure 4 is a perspective view of a forming tool, such as that of Figure 3, shown in cooperative relationship with an extremity of a conduit length for shaping such extremity, a portion of the conduit length being cut away;

Figure 5 is a perspective view of a forming tool

similar to that shown in Figure 4 but adapted for a somewhat different operation, a portion of the head of the tool being cut away for the sake of clearness;

Figure 6 is a view similar to Figure 3 showing a forming tool, such as that of Figure 5, in cooperative relationship with a conduit length;

Figure 7 is a fragmentary top plan view, with a portion cut away, of the forming tool shown in Figure 5; and

Figure 8 is a fragmentary perspective view of one of the shaping devices.

Referring now more particularly to the drawings, Figure 1 shows in central longitudinal cross-section a portion of a length 2 of extruded ceramic material just as it comes from the extrusion die and in the green or generally plastic state. The length is of generally octagonal external cross-section, as indicated in Figure 4, and is provided centrally thereof with a longitudinally extending duct 3.

In the extrusion process the green ceramic material is forced through a die and emerges in a straight continuous length of substantially uniform cross-section, such as the length shown in Figure 1.

The first step in the formation of conduit sections out of the extruded length comprises severing the length substantially perpendicularly to its axis to provide pieces of desired lengths the end faces of which are substantially plane and parallel. Such pieces at the time they are severed from the extruded length are of such consistency that they may be handled without substantial damage thereto, but the green ceramic material is readily workable and can be easily cut and shaped. After cutting the extruded length into the pieces mentioned, I preferably shape the ends of the pieces by means of suitable forming apparatus so as to produce generally similar conduit sections the respective ends of which interfit on being placed together, whereby to strengthen and assist in maintaining the integrity of the conduit thus formed.

I prefer to form one extremity of each conduit section as shown at the left-hand side of Figure 2 and the opposite extremity as shown at the right-hand side of such figure, although, if desired, both ends of a section may be similarly shaped and may cooperate with an end of an adjacent section shaped complementarily. The conduit section extremity shown at the left-hand side of Figure 2 is formed at the end of a piece cut as above described from the extruded length by removing a generally ring-shaped mass of the

green ceramic material from the inner portion of the end of the section. Similarly the conduit section extremity shown at the right-hand side of the same figure is formed at the end of a piece 5 cut as above described from the extruded length by removing a generally ring-shaped mass of the green ceramic material from the outer portion of the end of the section. Each of the generally ring-shaped masses of ceramic material which is 10 removed is tapered, as clearly indicated in Figure 2, and the respective ends are thus formed of complementary shape and are adapted to be moved together into interfitting relationship, the taper of the respective recesses and projections 15 enabling easy and precise centering. As the respective tapers are at the same angle and the depth of the recess in one extremity is substantially equal to the length of the projection on the other, the two extremities when pressed together 20 form a conduit whose internal and external cross-sections are substantially constant in spite of the joint.

Not only does this provision assist in strengthening the conduit, but it renders far simpler the 25 assembly of the sections than the prior method of utilizing dowel pins in holes provided in the extremities of the respective sections.

When the conduit is used for carrying electric 30 conductors the amount of protection and insulation afforded at the joints is precisely the same as throughout the bodies of the sections and no enlarged radially projecting portions are necessary. The joints may, if desired, be cemented or 35 tapered.

The shaping of the ends of the sections may be 40 performed either by hand or by machinery. For the sake of simplicity I have shown in the drawings a pair of hand tools, one for shaping one end of a preferred type of section and the other for 45 shaping the other end. In Figures 3 and 4 is shown a tool for shaping a conduit section extremity as shown at the right-hand side of Figure 2, and in Figures 5, 6, 7 and 8 is shown a tool for shaping a conduit section extremity as shown at the 50 left-hand side of Figure 2.

Referring now more particularly to Figures 3 and 4, the forming or shaping tool comprises a head 4 which is generally flat and with which is connected substantially centrally thereof and 55 extending substantially perpendicularly therefrom a generally cylindrical guiding portion 5 having a smooth exterior adapted to snugly fit within an extremity of a conduit duct whereby to guide the tool for generally rotatable movement with respect thereto. Connected with the 60 opposite face of the head 4 is a handle 6 suitable for manual operation for rotating the tool with respect to the duct.

The under portion of the head 4 outside the 65 guiding portion 5 is substantially flat and smooth and the head is provided at substantially equal intervals circumferentially thereof with notches or openings 7, as shown in Figure 4. Connected with the head at each of such openings and extending generally downwardly and circumferentially therethrough is a shaping device 8. Such device is made of strip metal bent in the manner shown and having a more or less sharp forward 70 edge 9.

The ceramic material of which the conduit section is made is, as above mentioned, plastic and easily workable in the green state although it is compressed sufficiently to offer firm guiding resistance to the forming tool. The guiding portion 75 5 of the tool is preferably made so as to fit snug-

ly but not tightly within the duct in the conduit section in such manner that there is no substantial lateral play. The portion 5 is made long enough so that it engages within the duct throughout a longitudinal distance sufficient to 80 prevent tilting of the tool. Furthermore, the guiding portion assists in supporting the green ceramic material from within and preventing the duct wall from becoming deformed during the forming operation. 85

The extremity of the guiding portion 5 of the tool is outwardly tapered, as shown at 10, to enable the tool to be easily inserted into the duct. One of the cut portions of the extruded length 90 of ceramic material is placed on end and the operator grasps the tool by the handle 6 and inserts the guiding portion 5 downwardly into the duct until the lower extremities of the shaping devices 8 contact with the end wall of the extruded length. The operator then simultaneously turns the tool in the clockwise direction and gently presses it downwardly substantially axially of the extruded length. The sharp forward edges 95 of the respective shaping devices cut into the green ceramic material and sever portions of the same from the end of the extruded length until the flat bottom surface of the head 4 comes into contact with the remaining portion of the end surface whereupon further movement of the tool axially of the extruded length is prevented. Slight 100 further rotation of the tool smooths off the cut surfaces and the end of the extruded length assumes the form shown at the right-hand side of Figure 2 and in Figures 3 and 4. The tool is then 105 withdrawn from the duct, the partially formed conduit section inverted and the opposite end operated upon by the same or a similar tool, preferably by a tool such as that shown in Figures 5, 6, 7 and 8, the operation being substantially the same as that above described except that an 110 interior rather than an exterior portion of the ceramic material at the end of the extruded length is removed so that the resultant effect is as shown at the left-hand side of Figure 2 and in Figure 6. During either or both of the forming operations 115 a core or mandrel-like supporting member may be inserted into the opposite end of the extruded length to assist in maintaining and supporting it in proper position and preventing undesirable deformation thereof. 120

The tool shown in Figures 5, 6, 7 and 8 is 125 similar to that shown in Figures 3 and 4 and corresponding reference numerals having primes affixed thereto denote the corresponding parts in the former figures. The openings 7' in the head 130 4' terminate at their inner extremities along the inner surface of the guiding portion 5' and the inner edges of the respective shaping devices 8' lie along the portion 5', and in fact are preferably inserted at least some distance into the 135 guiding portion so as to assist in supporting them. The effect of the tool is to remove a generally annular portion interiorly of the end of the extruded length, as above mentioned, the outwardly projecting portion of the head 4' having a 140 flat under surface cooperating with the remaining portion of the end of the extruded length to prevent further movement of the tool longitudinally thereof. 145

The respective shaping devices 8 and 8' are 150 formed to produce the tapered projections at the extremities of the conduit sections, as above described, whereby the sections will properly interfit and may be moved together into cooperative relationship without difficulty.

After the ends of the respective sections have been shaped, the sections are burned in the usual manner to produce finished conduit sections, as is usual in the art.

5 The forming of the ends of the sections may be accomplished in various different ways, such, for example, as simply by a pressing and deforming operation which is possible on account of the plastic condition of the material, but I find it more satisfactory to use more or less pointed shaping devices which substantially cut into the material and shave off ribbon-like elongated strips as the tool is rotated and moved longitudinally of the extruded length. Although I prefer to guide the tool internally of the conduit section by means of the duct wall, the tool may be guided otherwise, such, for example, as by the outer surface of the section, particularly when round sections are being made.

20 The invention is equally applicable to single duct and multi-duct conduit, the end of the section at each duct being formed in the manner explained. The invention is further applicable to curved or twisted sections, and in fact the particular form of the section is immaterial, as will be appreciated. The terms "conduit section" and "conduit length" and similar expressions as used in the claims are not to be construed as being limited to conduit sections whose axes are straight lines, but also comprehend sections of other shapes.

The invention is not limited to the production of conduit sections of ceramic material, but in its broader aspects is equally adapted for use with other materials, plastic and non-plastic, in various forms.

In my copending application Serial No. 545,779, filed of even date herewith, I have described and claimed the conduit and conduit sections as well as the methods of making the same which are described herein, and therefore no claim is made herein specifically to such conduit, conduit sections or methods.

While I have shown and described certain present preferred embodiments of the invention, it is to be distinctly understood that the same is not limited thereto but may be otherwise variously embodied within the scope of the following claims.

50 I claim:

1. Forming apparatus for shaping an end of a conduit section, comprising a portion adapted to engage within a duct in the conduit section for guiding the forming apparatus, said portion being guidable solely by the conduit section itself, and a second portion connected with the first for shaping an end of the conduit section upon guided movement of the forming apparatus relative to the duct.

60

65

70

75

2. Forming apparatus, comprising a generally cylindrical guide portion adapted for insertion into a conduit duct for guiding the forming apparatus relatively to such duct, said cylindrical guide portion being guidable solely within said conduit duct, and shaping means connected with such guide portion and effective upon relative movement of the forming apparatus and conduit for shaping an end of the conduit adjacent the duct.

3. Forming apparatus, comprising a rotatable body having a portion for guiding it for generally planar rotatable movement relatively to a conduit section, said portion being guidable solely by the conduit section itself, and means carried by the body and effective for cutting away an annular portion of the conduit section upon generally rotatable movement of the forming apparatus relatively thereto.

4. Forming apparatus, comprising a rotatable member having means for guiding it for generally rotatable movement relatively to a conduit section, and a series of inclined cutters extending generally parallel to the plane of rotation of the rotatable member and spaced about the rotatable member for shaping an end of the conduit section upon generally rotatable movement of the forming apparatus relatively thereto.

5. A forming tool comprising a head, said head having openings therein, and cutting members connected with the head and extending downwardly and angularly therefrom generally below such openings.

6. A forming tool comprising a generally rotatable head, a generally cylindrical guide member extending therefrom, and a series of inclined strip metal shapers extending from said head, spaced circumferentially thereof, and disposed generally about said guide member.

7. A forming tool comprising a generally rotatable head having a guiding surface, said surface having circumferentially spaced openings therein, said head having connected therewith and extending substantially centrally of said openings a generally cylindrical guide member, and a series of shapers extending from said head substantially opposite said openings and disposed generally about said guide member.

8. Forming apparatus for shaping an end of a conduit section, comprising a guide cooperable with the conduit section for rotatably guiding the forming apparatus and bearing against said section so that the guiding of the forming apparatus is effected by the section itself, and means connected with the guide for removing a portion of the conduit section upon rotation of the forming apparatus.
